(57) **CLAIM**

The ornamental design for a keyboard with protective cover, as shown and described.

DESCRIPTION

FIG. 1 is a perspective view of a keyboard with protective cover showing our new design;

FIG. 2 is another perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is a perspective view thereof showing the keyboard with protective cover in the closed status; and,

FIG. 10 is another perspective view thereof showing the keyboard with protective cover in the closed status.

The broken lines illustrate portions of the keyboard with protective cover that form no part of the claimed design.

1 Claim, 8 Drawing Sheets
